COMBINED PROFESSIONAL COMB AND
SCALE

Carmine Claps, Pleasantville, N. Y.

Application August 19, 1950, Serial No. 180,427

3 Claims. (Cl. 132—11)

1

This invention relates to new and useful improvements in implements for barbers, hair-dressers and the like; and, more particularly, the aim is to provide a novel and valuable professional comb which is so constituted that a hairdresser, in using a pair of scissors or shears, may be guided, while cutting or trimming the hair of a customer, to insure that the hair will be cut to the intended length.

As is well known, the operation of hair cutting or trimming as performed by a barber or hairdresser involves, except at the locations where the hand tool known as a clipper is applied, the conjoint use of a comb and a pair of scissors or shears; the comb for lifting strands or a tress of hair into position for cutting, and the shears for effecting the cut. The clipper is rarely if ever used on a woman's head, and only at certain minor places on a man's head, even where a man is willing to permit a clipper to be used at all. The manipulation of comb and shears requires, especially, a high degree of care and skill; otherwise differently located clumps of hair strands will be cut to such incorrectly differing lengths that the appearance of the hair after an attempt to cut, trim or dress it will be worse than before and perhaps quite unkempt and ragged.

This invention will help the hair stylist to follow the creation of a new hair style. For example, to measure the length of the hair desired at the nape of the neck, above it, the side length and the front of the head, and by so doing the created or prescribed style will be copied correctly by beauticians, or hairdressers.

By the present invention, however, there is provided an implement comprising a professional comb combined in a special way with a scale calibrated in terms of linear measurement, as inches. Since said scale is extended or extensible longitudinally of the comb, a comparatively inexperienced barber or hairdresser may readily manipulate the comb, relative to a strand of hair, to cause that strand to be disposed in such position that when the shears is applied thereto at the customary distance above the comb teeth said strand will be cut to precisely a desired length. This length, for instance, may be one requested by the customer.

While the invention attains its chief utility in a professional comb, that is, one used by hair-dressers and ordinarily 7" long, the invention may be applied to a pocket comb, as one 5" or 6" long. Such a pocket comb, for instance, may well be in the possession of any one, for self use,

2

as to facilitate an occasional trimming operation by the aid of an ordinary pair of scissors.

A feature of the invention is that said scale is so carried by the comb that its calibrations by direct readings therefrom give true lengths.

Another feature of the invention is that scale calibrations may be carried by the comb along a side thereof, or along opposite sides thereof, or along the top thereof, or along a side and the

10 top thereof.

A further feature of the invention is that the scale calibrations may be of various kinds, as one in inches and another in centimeters. This scale may be inscribed on the comb body or in an indented strip of metal, such as stainless steel, aluminum, or of any other durable material.

Still another feature of the invention is that the scale or scales carried by the comb may be directly carried by the later, or carried by an auxiliary member easily and inexpensively added to the combination.

Still another feature of the invention is that the comb may carry a plurality of different scales, as one for giving measurements in centimeters and fractions thereof, whereby quick and easy reading of either scale as revised may be had, and this without any chance of a fractional factor of one kind of measurement being confused with a fractional factor of the other kind of measurement.

30 Yet a further feature of the invention is that the advantages just above recited, as well as one or more others, are attained by virtue of the fact that some of the calibrations of each scale are directly carried by the comb and another or other calibrations of each scale are carried by the auxiliary member aforesaid.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 side elevationally shows one now favored embodiment of the invention.

Fig. 2 is a transverse section, taken on the line 2—2 of Fig. 1.

50 Fig. 3 is a view similar to Fig. 1, but showing a modification.

Fig. 4 is an end elevation of the implement of Fig. 3, looking toward either end thereof.

55 Fig. 5 shows, detached, the auxiliary scale carrying member of Figs. 3 and 4, looking at the

side of said member opposite to the side thereof seen in Fig. 3.

Fig. 6 is also a view similar to Fig. 1, but showing a further modification.

Fig. 7 is an end elevation of the implement of Fig. 6, looking toward either end thereof.

Fig. 8 is a top plan view of Fig. 6.

Fig. 9 is another view similar to Fig. 1, but showing still a further modification.

Fig. 10 is an enlarged end elevation of Fig. 9, looking toward the right in that view.

Fig. 11 is a view side elevationally showing another now favored embodiment of the invention.

Fig. 12 is an end elevation thereof, looking toward the right in Fig. 11.

Fig. 13, fragmentarily, is a view similar to Fig. 11, but showing the parts in a different adjustment.

Fig. 14 is a view corresponding to Fig. 11, but looking at the side of the implement undermost in Fig. 11.

Fig. 15 is an end elevation, looking toward the right in Fig. 14.

Fig. 16, fragmentarily, is a view similar to Fig. 14, but showing the parts in a different adjustment.

The hairdresser's implement, according to the first form of the present invention shown in Figs. 1 and 2, includes a comb 15 having a main longitudinally extending portion 16 constituting the back from which are extended the comb teeth; this comb being further shown as having a line of fine teeth 17 and a line of coarse teeth 18, as being molded for instance from hard rubber, and as being a professional comb 7" long.

In this comb of Figs. 1 and 2, the scale of the invention is shown as comprising a line of calibrations 19 indented in and spaced one inch from one another along a side of the backing 16. The comb 15 being, as just stated, 7" in length, there are six of these calibrations 19. Reading from left to right in Fig. 1, the calibrations 19 are marked, respectively, as also by indentations in the backing 16, "1," "2," "3," "4," "5" and "6." Said "1" will be noted in Fig. 2, at 20; said "1" being also having the same reference numeral 20 applied thereto in Fig. 1. Note that the end of the comb 15 at the left in Fig. 1, lies in a line 21 which is perpendicular to the direction of length of the scale including the calibrations 19. Said line, in said direction, is distant one inch from the calibration 19 marked "1." Consequently, the scale is so carried by the comb that its calibrations by direct readings therefrom give true lengths.

Also, said scale is a full 7" scale, because the end of the comb 15 at the right in Fig. 1 lies in a line 22 which is perpendicular to the direction of length of the scale, and said line 22, in said direction, is one inch from the calibration 19 associated with the marking "6."

Barbers and hairdressers, like others, are more often right handed than left handed. A right handed barber or hairdresser, in using comb and shears for hair cutting or trimming, would hold the comb in his left hand and the shears in his right hand. In such case, the scale should extend, in the direction of increase of lineal value of the successive calibrations, from left to right, along the side of the comb to be held uppermost; as shown in Fig. 1.

To adapt the new combined comb and scale to ready use by a left handed barber or hairdresser, the comb 15 desirably and also pursuant

to the invention, would be provided along its side opposite to its side seen in Fig. 1 with a line of calibrations exactly corresponding to the calibrations 19 and similarly marked, and with the marking corresponding to the marking "1" opposite the marking "1," the marking corresponding to the marking "2" opposite the marking "2," the marking corresponding to the marking "3" opposite the marking "3," and so on; in other words, the two scales and their calibrations and markings will be such that Fig. 1 may be taken as showing one side or the other of the comb 15.

As a consequence, the same comb 15, when held in the right hand of a left handed hairdresser and so freeing his right hand for use of the shears, would present its scale to extend, in the direction of increase of lineal value of the successive calibrations, from right to left, if he so grasped the comb that the side thereof undermost in Fig. 1 would now be the side thereof uppermost.

As will be understood, there may be additional and minor calibrations between the calibrations 19, as to indicate half-inch or quarter-inch, one-eighth, or one-sixteenth division.

It is also to be understood that the calibrations may be pursuant to the metric system, as indicative of centimeters and a fraction or fractions thereof, or said calibrations may be according to any arbitrary scale of linear measurement.

Referring to the form of the invention shown in Figs. 3, 4 and 5, wherein the parts to which are applied reference numerals with primes added correspond, respectively, to the parts to which have been applied the same reference numerals without primes, it will be noted that in these views, by way of example, half-inch calibrations 23 are indicated as included in the scale having the inch calibrations 19.

40 The backing 16' is longitudinally slotted as at 24, and in this slot is an auxiliary member 25, carrying on one side, as shown in Fig. 3, a scale identical with the scale of Fig. 1 except for the addition as just stated of said half-inch calibrations 23. The member 25 may be of any selected material, as metal or a plastic, and its markings may be indented therein, engraved therein, or otherwise marked therein or thereon; and to render said markings readable the comb 15' is made of transparent material.

45 The reverse side of the auxiliary member 25, as seen in Fig. 5, is provided with a scale to indicate measurements according to the metric system. Here the calibrations designated 26 are spaced one centimeter one from another; and to make easy the quick reading of markings in terms of centimeters, such markings, as indicated at "3," "6," "9," "12" and "15" are applied at points spaced a distance of three centimeters one from another.

60 Referring to the form of the invention shown in Figs. 6, 7, and 8, here the parts to which are applied reference numerals with double primes added correspond, respectively, to the parts to which have been applied the same reference numerals without primes. To simplify the drawing, the line or lines of teeth present are indicated merely, as having such teeth extended between the dot and dash lines 27 and 28. The auxiliary member 25" is a slide having a shaped bottom rib 29 the dove-tail cross-section of which from end to end of said member is the same as that of the groove 24", which latter is of constant cross-section from end to end thereof, as 65 is the groove 24. The calibrations 19", it will be

noted, are partially at a side edge of the upper main portion of the member 25" and partially at the top of said main portion of the member 25", and the markings "1," "2," "3," etc., representing inches, are placed at the top of said main portion of the member 25" adjacent to the appropriate calibrations.

Referring to the form of the invention shown in Figs. 9 and 10, wherein the parts to which are applied reference numerals with the suffix *a* added correspond, respectively, to the parts to which have been applied the same reference numerals but without such suffix, an implement according to the invention is shown which incorporates a pocket comb 5" long. The comb 15^a is of transparent material, so that opposite sides of the auxiliary member 25 have scales, pursuant to the principles explained in connection with Figs. 3 and 5 or otherwise. One of such scales can be seen in Fig. 9, this scale including the inch scale calibrations 19^a and appropriately associated therewith the markings "1," "2," "3," and "4." All along its length and at its bottom the auxiliary member 25^a has an inclined outer wall, to establish at 29^a what may be called a half dovetail, thereby to make of the member 25 a slide like the slide 25".

Referring to the form of the invention illustrated in Figs. 11 through 16, a comb 30 is shown which is exactly like the comb 15^a in respect to the backing 31, this corresponding to the backing 16^a, and the groove 32, this corresponding to the groove 24^a, and the fact that the comb, at least at its said backing, as is desirable although not essential, of transparent material. Here also, there is included, for being received retentively yet slidingly in said groove, an auxiliary member 33, this corresponding to the auxiliary member 25^a.

The form of the invention now being described is further shown as carrying scales calibrated one in inches and the other in centimeters, the inch calibrations being on the side of the implement seen in Figs. 11 and 13 and the centimeter calibrations being on the side of the implement seen in Figs. 14 and 16. The inch scale calibrations, 34, each measuring off a full inch, and so individually associated with the markings "1," "2," "3," etc., are on the back 31. The metric scale calibrations, 35, each measuring off a full centimeter, are also on the back 31; these having the markings "3," "6," "9," etc., associated therewith, to emphasize the identity of the calibrations respectively designating a three-centimeter measurement, a six-centimeter measurement, a nine-centimeter measurement, and so on.

Note further that the end of the comb 30 which lies at the left in Fig. 11 lies in a line 36 which, perpendicular to the direction of length of the scale including the calibrations 34, is distant one inch from the calibration marked "1." Note, too, that the opposite end of the comb 30, which comb end is the one lying at the left in Fig. 14, lies in a line 36' which, perpendicular to the direction of length of the scale including the calibrations 35, is distant one centimeter from the nearest one of the calibrations 35. Thereby, so far as full units of measurement are concerned, both the scales carried by the comb are true scales in terms of the length of the comb itself, with the zero point of each scale at an appropriate end of the comb.

But the two scales carried by the implement are not, however, merely full units of measurement scales. They are, in addition, scales for

adding fractions of a unit of measurement to any selected unit or plurality of full units of measurement. The auxiliary member 33 at the end portion thereof at the left in Fig. 11 carries a calibration 37 which is one-half inch from the adjacent end of said member, another calibration 38 which is one-quarter inch from said end of said member, and another calibration 39 which is three-quarters of an inch from said end of said member. Also, said auxiliary member 33, at the end portion thereof at the left in Fig. 14, carries a calibration 40 which is distant one-half of a centimeter from the adjacent end of said member.

Desirably, as will now be appreciated, the auxiliary member 33 is sufficiently opaque so that reading of a calibration 37, 38 or 39 will not be accompanied by a confusingly visible reading of the calibration 40, and vice versa.

Said member 33 is fitted in the groove 32, 20 snugly, and yet slidably; so that while said member may be endwise moved along said groove, either to be fully housed therein as in Figs. 11 and 14, or to be partially projected from the comb 33 at either end of the latter, friction may be depended on to hold said member against accidental or casual shift from any projected position to which it has been manually adjusted.

Said projection of the auxiliary member 33 will be to prepare the implement for use in aid of a cutting of a hair tress or clump to a length equal to some desired one represented by one or more full units of measurement plus a fractional part of one such unit as determined by the extent of said projection of said member 33. Thus, where the scale having the inch calibrations 34 is employed, then, obviously, with the side of the comb 30 seen in Fig. 11 uppermost, and with the member 33 having previously been projected, for instance, to the extent indicated in Fig. 13, the hair may be readily cut to a length of 1 1/4", 2 1/4" or 3 1/4", and so on, merely by observation of the scale having the calibrations 34 at the instant of application of the shears. Similarly, where the metric scale having the centimeter calibrations 35 is employed, then with the side of the comb seen in Fig. 14 uppermost, and with the member 33 having previously been projected, for instance, as in Fig. 16, the hair may be readily cut to a length of 1.5 cm., 2.5 cm. or 3.5 cm., and so on, merely by observation of the scale having the calibrations 35 at the instant a snipping operation is effected at the shears.

Due to the fact that the bottom portion of the auxiliary member or slide 33, where cross-sectionally enlarged as at 41, is of what may be called half dovetail form, said member is not receivable in the groove 32 except in a way properly significantly to associate such calibrations as those typified at 37, 38 and 39 with only the scale appropriate thereto, that is, the scale including the calibrations 34, and consequently said member must also be received in the said groove in a way properly significantly to associate such calibrations as typified at 40 with the scale appropriate thereto, that is, the scale including the calibrations 35.

Furthermore, since a professional comb, that is, one used professionally by a barber or hairdresser, has a straight top edge 42 for its back 31 as illustrated, and since the auxiliary member 33 may, also as shown, have a matchingly straight top, visual detection is instantly made of an accidental and unintended projection of an end of the member 33 beyond an end of the comb; thereby to insure that when either scale at its calibrations

on the comb is to be read for measurements during hair cutting or trimming, it will be the appropriate end of the comb, and not an end of the member 33 projected beyond a comb end, which rests against the scalp.

While I have illustrated and described the preferred embodiments of my invention, it is to be understood that I do not limit myself to the precise constructions herein disclosed and the right is reversed to all changes and modifications coming within the scope of the invention as defined in the appended claims.

Having thus described my invention, what I claim as new and desire to secure by United States Letters Patent is:

1. A combined comb and measuring scale, wherein the scale is calibrated in terms of units of linear measurement, said scale extended along the length of the comb and so in a direction substantially at right angles to the directions of length of the comb teeth, said scale having its zero point contained in a line marking one end of the comb, said line substantially perpendicular to the direction of extension of the scale, said scale being at one side of the comb, there being another scale at the opposite side of the comb, the comb at its backing being of transparent material and along its said backing having a groove, and there being an auxiliary member in said groove, said member carrying on one of its sides one of said scales and on its opposite side the other of said scales, said groove laterally thereof having an undercut portion, and said auxiliary member having a cross-section matching that of said groove, whereby said member may be endwisely inserted into the groove then to be held therein against other than endwise removal therefrom.

2. A combined comb and measuring scale, wherein the scale is calibrated in terms of units of linear measurement, said scale extended along the length of the comb and so in a direction substantially at right angles to the directions of length of the comb teeth, said scale having its zero point contained in a line marking one end of the comb, said line substantially perpendicular to the direction of extension of the scale, said scale being at one side of the comb and including calibrations on the comb backing each representing a terminus of a full unit of measurement pursuant to said scale, there being another scale at the opposite side of the comb and including calibrations on the comb backing each representing a terminus of a full unit of measurement pursuant to such other scale, said units of one of said scales being different from said units of the other scale, the second-named scale also having its zero point contained in a line marking one end of the comb substantially perpendicular to the direction of extension of said scale, said backing having a groove at the top of the comb extending longitudinally and from end to end thereof, there being an auxiliary strip-like member slidable in said groove, said member on one side thereof being calibrated to mark off thereon a subdivision of the length thereof equal to a predetermined fractional part of the distance between two adjoining calibrations of the first-named scale and said member on the opposite side thereof being calibrated to mark off thereon a subdivision of the length thereof equal to a

predetermined fractional part of the distance between two adjoining calibrations on the second-named scale.

3. A combined comb and measuring scale, wherein the scale is calibrated in terms of units of linear measurement, said scale extended along the length of the comb and so in a direction substantially at right angles to the directions of length of the comb teeth, said scale having its zero point contained in a line marking one end of the comb, said line substantially perpendicular to the direction of extension of the scale, said scale being at one side of the comb and including calibrations on the comb backing each representing a terminus of a full unit of measurement pursuant to said scale, there being another scale at the opposite side of the comb and including calibrations on the comb backing each representing a terminus of a full unit of measurement pursuant to such other scale, said units of one of said scales being different from said units of the other scale, the second-named scale also having its zero point contained in a line marking one end of the comb substantially perpendicular to the direction of extension of said scale, said backing having a groove at the top of the comb extending longitudinally and from end to end thereof, there being an auxiliary strip-like member slidable in said groove, said member on one side thereof being calibrated to mark off thereon a subdivision of the length thereof equal to a predetermined fractional part of the distance between two adjoining calibrations of the first-named scale and said member on the opposite side thereof being calibrated to mark off thereon a subdivision of the length thereof equal to a predetermined fractional part of the distance between two adjoining calibrations on the second-named scale, said groove being of constant cross-section from end to end of the comb with said cross-section such that the groove is non-symmetrically undercut, and said calibrations on the opposite sides of said auxiliary member being so placed thereon that said member may be received in said groove only in a way properly visually significantly to correlate one of said calibrated sides of said member with the calibrations on the appropriate side of the comb backing and consequently in a way properly visually significantly to correlate the other calibrated side of said member with the scale calibrations on the side of the comb backing opposite to the side thereof last-named.

CARMINE CLAPS.
